UNITED STATES PATENT OFFICE.

EDGAR E. GREVE, OF PITTSBURGH, PENNSYLVANIA, ASSIGNOR TO OIL WELL SUPPLY COMPANY, OF PITTSBURGH, PENNSYLVANIA, A CORPORATION OF PENNSYLVANIA.

APPARATUS FOR BORING OIL AND ARTESIAN WELLS.

1,098,147.

Specification of Letters Patent. Patented May 26, 1914.

Application filed July 22, 1912. Serial No. 710,730.

To all whom it may concern:

Be it known that I, EDGAR E. GREVE, a citizen of the United States, residing at Pittsburgh, in the county of Allegheny and State of Pennsylvania, have invented certain new and useful Improvements in Apparatus for Boring Oil and Artesian Wells; and I do hereby declare the following to be a full, clear, and exact description of the invention, such as will enable others skilled in the art to which it appertains to make and use the same.

My invention relates to the construction of that class of devices commonly employed in boring oil and Artesian wells wherein the boring or drilling tool is detachably connected with its stem.

The invention is more especially directed to what is known as hydraulic boring for deep wells wherein a tubular sectional stem is employed and a flow of water through the stem and boring tool is employed to remove the detritus.

The general construction of this class of devices includes a stem comprised of threaded sections connected by threaded couplings, the lower section of the stem being provided with a threaded drill collar to which the drill or boring tool is secured by a threaded connection.

In drilling or boring with this class of devices, when the rotary method is followed, it frequently occurs that the drill or bit, or the drill collar with the drill or bit, becomes detached leading to a troublesome and often expensive "fishing" job to recover the detached parts and with possibly ultimate loss of the well. Also, in the case of hydraulic boring apparatus where a tubular drill stem is used and water is pumped down therethrough to remove the detritus from the well, it often happens that a pocket of gas is struck the back pressure from which arrests the down flow of water from the pump, forces the water back and carries the detritus through the bit into the lower section of the stem, which results in plugging the bit.

The object of the present invention is, therefore, two fold, first to provide means whereby the operator is given timely warning that the bit or the drill-collar is likely to become detached, and second to provide means for preventing the plugging of the bit when back pressure occurs.

To this end one feature of my invention

embraces the combination with the bit and stem of a drill tool, of a valve for arresting the flow of water, said valve being actuated from the bit and drill-collar.

A second feature of my invention embraces the combination with the drill stem and bit, of a valve actuated by back pressure in the well to prevent the detritus plugging the bit.

There are other, minor, features of invention involving particular combinations and elemental features of construction, ancillary to the main features of invention, all of which will hereinafter more fully appear.

In the drawings chosen for the purpose of illustrating my invention, the scope whereof is pointed out in the claims, Figure 1 is a view of a drill stem, drill-collar and portions of a bit, together with the adjuncts thereto which involve my invention, the drill stem and drill collar being shown in longitudinal central section. Fig. 2 is a detached perspective view of the valve which is actuated from the drill bit or drill-collar. Fig. 3 is a detached view, in elevation, of the valve seat for the valve shown in Fig. 2, also showing the valve which is closed by back pressure in the well. Fig. 4 is a top or plan view of the valve seat shown in Fig. 3. Fig. 5 is an edge view of the bit, taken at right angles to the bit shown in Fig. 1.

Like symbols refer to like parts wherever they occur.

I will now proceed to describe my invention more fully so that others skilled in the art to which it appertains may apply the same.

In the drawings, A indicates the lower section of a tubular drill stem, A' the section of the stem next above, A² the coupling which connects the sections A, A' of the stem, B the drill-collar on the lower end of lower section A, and C the bit, the threaded shank c of which is screwed into the bit collar B.

D, D indicate ports or passages extending through the shank c of the bit C.

All of the above noted parts may be of the usual or any approved construction the parts being connected by right hand threads in the usual manner.

1 indicates a disk of suitable diameter having a threaded periphery and adapted to be interposed in coupling A², between the

stem sections A' and lower section A which carries the drill collar B and bit C. This disk 1 is perforated centrally as at 1^a to afford passage for water in case of a hydraulic boring device, and to constitute an upper valve seat 2 for valve 5, and a lower valve seat 3 for valve 8. The disk 1 is also provided on its upper surface with studs 1^b that a wrench may be used to insert the disk 10 into and remove it from the coupling A². On its under surface the disk 1 is provided with a plurality of studs or pins 1^c, preferably four, which serve as guides or stems for the back pressure valve 8.

15 4 indicates a rod whereby an operative connection is established between the bit C, drill-collar B and the valve 5 which controls the downward flow of water through the drill stem. This rod 4 is connected at its 20 lower end with the bit C through the medium of a swivel 6 and eye bolt 6^a said bolt having a left hand thread, or thread the reverse of that which connects the stem sections, drill-collar and bit. The upper end 25 of rod 4, which carries the valve 5, is perforated as at 4^a with a series of holes for the pin 7 which carries the valve 5.

The valve 5, which is preferably hemispherical, is perforated for the passage of 30 rod 4 and is adjustably connected to rod 4 by means of eye bolts 7^a screwed into the upper surface of the valve 5 and through which eye-bolts the pin 7 passes.

7^b, 7^c indicate collars on pin 7, and 7^d, 7^e, 7^f set screws for holding pin 7 in proper relation to rod 4 and valve 5. It is intended 35 that this valve 5 shall be drawn down on its seat by any movement of the bit C or drill collar B which tends to detach said parts or 40 either of them from the section A of the drill stem. As illustrated in the drawing the valve 5 will be drawn down on its seat when the shank of the bit has moved out of the drill-collar for one half the length of 45 the thread of the bit shank, or the drill-collar B has moved down an equivalent distance on the lower section A of the stem. The extent of movement of the bit on the drill-collar or the drill-collar on the stem 50 which shall seat valve 5 is not material, and is left to the discretion of the constructor, but as the length of the lower stem sections A may vary, the series of pin holes 4^a in the upper end of rod 4 has been provided that 55 any required adjustment of valve 5 on rod 4 may be made. The valve 5 having been drawn down on its seat by the change in the relation of bit and stem, the arrest of the flow of water through the stem thereby 60 caused will cause the pumps to shut down, thus warning the operator that the bit or drill collar is loose and there is a necessity for pulling out the drill.

8 indicates the back-pressure valve which 65 is suspended from the under side of the disk

1. The back-pressure valve 8 is in the form of a disk having openings for the passage of the rod 4, and the studs or pins 1^c on the under side of disk 1. The rod 4 and pins 1^c pass through the valve disk 8 with a moving fit and the back-pressure valve is prevented from escaping by nuts N and jam nuts n or their equivalents.

The construction of the apparatus being substantially such as hereinbefore pointed out, it will operate as follows: Assuming the several parts of the apparatus to occupy the relation to each other indicated in Fig. 1 of the drawing, during the operation of the hydraulic drill the water delivered by the 70 pumps will flow down through the tubular stem A' around valve 5, through the valve seat in disk 1, around back-pressure valve 8 down through lower stem section A and thence out through passages D, D in the bit, 75 into the bore of the well whence it will move upward carrying with it the detritus. If now in operating by the rotary method either the bit or the drill-collar begin to unscrew from the stem and become detached 80 therefrom such movement will draw the valve 5 down on its seat and close the tubular drill stem above section A and coupling A² which will cause the pumps to shut down, thus signaling the operator that something 85 is wrong with the drill. If at any time during the drilling operation a gas pocket is opened the back pressure from the pocket will, if sufficiently strong, reverse the current and force the detritus through the ports 90 or passages D, D in the shank of bit C. This, if not prevented, will result in plugging the bit, and compel the withdrawal of the bit from the well with attendant labor 95 and loss of time. Under such circumstances, however, with the construction hereinbefore set forth, the back pressure and reversed current immediately close the back-pressure valve 8 thus checking the flow and preventing 100 the detritus from entering and plugging 105 the bit.

Having thus described my invention, what I claim and desire to secure by Letters Patent is:

1. In apparatus for drilling wells, the combination of a bit, a tubular stem therefor, a valve located in the tubular stem, and means for actuating the valve by a relative movement of the bit and stem.

2. In apparatus for drilling wells, the combination of a bit, a tubular stem therefor, a valve located in the tubular stem, and means for connecting the valve and bit.

3. In an apparatus for drilling wells, the combination of a bit, a tubular stem therefor, a valve located in the tubular stem, and a rod having a loose connection with the bit for connecting the valve and bit.

4. In an apparatus for drilling wells, the combination of a bit, a tubular stem there-

for, a valve located in the tubular stem, and a rod for actuating the valve, said rod having a swivel connection with the bit.

5. In an apparatus for drilling wells, the combination of a bit, a tubular sectional stem therefor, a valve located in the tubular stem, means for connecting the valve with the bit, and means for adjusting the valve to change the distance between the bit and

10. valve.

6. In an apparatus for drilling wells, the combination of a bit, a tubular sectional stem therefor, a coupling for the stem sections, a valve seat interposed between the sections of the tubular stem, a valve located in the tubular stem, and means for actuating the valve by a relative movement of the bit and stem.

7. In apparatus for drilling wells, the combination of a tubular stem, a back pressure valve arranged in the stem said valve having an opening therethrough, a bit, means for preventing the separation of bit and stem said means extending through the opening in the valve, and movable means for limiting the movement of the means which prevents the separation of the stem and bit.

8. In apparatus for drilling wells, the combination of a tubular stem, valve seats 30 arranged therein, a bit, a back pressure valve having an opening therethrough, a valve for preventing the downward flow of fluid in the stem and means for actuating the last named valve by a relative movement of the bit and stem, said means extending through the opening in the back pressure valve.

9. In a device of the character described, the combination with a well casing, of a bit, 40 a water controlling valve, and means for connecting said bit and said valve adapted to cause a closing of said valve when said bit is broken from the casing.

10. In a device of the character described, 45 the combination with a rotary casing provided with a bit at the lower end, of means actuated by the bit when broken from the casing for giving an indication of that fact at the top of the casing.

In testimony whereof I affix my signature, in the presence of two subscribing witnesses.

EDGAR E. GREVE.
